DESIGN FOR A HEAT INSULATED JUG

Eugene Schwarz, Alexandria, Ind., assignor to
The Mantle Lamp Company of America, Chi-
cago, Ill., a corporation of Illinois

Application May 22, 1939, Serial No. 85,126

Term of patent 14 years

To all whom it may concern:

Be it known that I, Eugene Schwarz, a citizen
of the United States of America, residing at
Alexandria, in the county of Madison and State
of Indiana, have invented a new, original, and
ornamental Design for Heat Insulated Jugs, of
which the following is a specification, reference
being had to the accompanying drawing, form-
ing a part thereof.

The figure is a view in front elevation of a
heat insulated jug, showing my new design.

I claim:

The ornamental design for a heat insulated jug,
substantially as shown.

EUGENE SCHWARZ.
